UNITED STATES PATENT OFFICE.

CHARLES W. BURROWS, OF WASHINGTON, DISTRICT OF COLUMBIA.

ELECTROMAGNETIC DEVICE.

1,340,698.

Specification of Letters Patent.

Patented May 18, 1920.

Application filed April 27, 1917. Serial No. 164,892.

To all whom it may concern:

Be it known that I, CHARLES W. BURROWS, a citizen of the United States, residing in the city of Washington, District of Columbia, 5 have invented certain new and useful Improvements in Electromagnetic Devices, of which the following is a specification.

My invention relates to electromagnets.

I will describe one form of electromagnet 10 embodying my invention and will then point out the novel features thereof in claims.

In the accompanying drawings, Figure 1 is a view showing in front elevation one 15 form of electromagnet embodying my invention. Fig. 2 is a view showing in end elevation the electromagnet shown in Fig. 1. Fig. 3 is a transverse sectional view taken on the line III—III of Fig. 1 looking in the direction of the arrows.

20 Similar reference characters refer to similar parts in each of the several views.

Referring to the drawings in detail, the 25 electromagnet comprises in this instance two cores designated C and C', respectively, each being formed of magnetizable material, usually soft iron, and preferably circular in cross-section. Each core is provided with 30 enlarged end flanges P, P' of magnetizable material, also usually of soft iron, which flanges are preferably, though not necessarily, integral with the body of the core. Each core, therefore, constitutes in itself a 35 spool on which a wire coil W may be wound, and the lower flange P' of each core also constitutes the pole-piece for such core.

Each core with its flanges is preferably 40 provided with a coating of enamel to insulate the winding from the iron, thus providing an insulation of minimum thickness and so bringing the wire as close as practicable to the iron. The entire core with its flanges 45 may be dipped in the enamel, and the enamel may then be removed from the outer ends of the flanges. The enamel remaining on the edges of the flanges prevents rusting and also assists in avoiding electric surface leakage.

As here shown, the cores C and C' are 50 arranged in parallel spaced relation and are rigidly connected at their upper ends by a back strap B and at their lower ends by a strip S. The back strap B is formed of magnetizable material, usually soft iron, and is secured to the upper ends of the cores 55 by screws E, E. The back strap is of such size and contour that it engages with the

flanges P, P' through their entire area, thus giving a large area of contact between the cores and the back strap and so reducing to a minimum the magnetic reluctance of this 60 part of the magnetic circuit. To further decrease the reluctance of this part of the circuit, the flanges P, P' may be arranged in mutual contact, as shown. The strip S connecting the pole-piece flanges P' and P' is 65 formed of non-magnetizable material, such as brass, and as here shown is secured to the rear edges of the flanges P', P' by screws F, F. The length of strip S is such that it projects beyond the outer edges of the 70 flanges. Each projecting end of the strip S is provided with a bracket L secured to the strip by screws K, K, a portion of the bracket depending from the strip and being provided with a threaded orifice to receive 75 a bearing screw R. The inner ends of the bearing screws R, R constitute pintles for pivotally supporting an armature A.

The rear edge of the armature A is provided with ears D, D in which the pintles 80 R, R are journaled. It will be seen, therefore, that the pivotal points of the armature are laterally displaced from the pole-pieces, and that there is practically no part of the armature back of the axial line of the 85 pivotal points. Consequently, the torque around the pivotal axis exerted on the armature by the magnet is all in the same direction, and no back torque can exist to retard the movement of the armature. 90

It will be noted from the drawing that the armature A overhangs the pole-pieces P', P' on all sides except the back. The purpose of this construction is to cause as much as possible of the magnetic flux from 95 the pole-pieces to pass through the armature and so to utilize to the highest possible degree the flux created by current in the windings W, W.

The flanges P and P' are preferably 100 rectangular, as shown, thus providing the greatest possible area for engagement with the back strap and for coöperation with the armature, and so assisting to reduce the reluctance of the magnetic circuit. I have also 105 found that the flanges P', P' constituting the pole-pieces of the magnet, may advantageously be dis-symmetrical with respect to the core body; that is, that these flanges may be extended in one direction or the other 110 from the center of the core body in the general direction of the plane of the two core

bodies. The exact amount of such dis-symmetry must be determined in each case by experiment.

The strip S, as here shown, is provided at 5 its medial portion with an arm V formed of non-magnetizable material and arranged between the pole pieces P', P', which arm maintains the cores C and C' in parallel spaced relation. The free end of the arm V 10 projects beyond the edges of the pole pieces and is provided with a screw T adjustably mounted therein, such screw being locked in any adjusted position by means of a nut t. This screw T is provided for the purpose of 15 determining the attracted position of the armature A, it being understood that by adjusting the screw within the arm V the attracted position of the armature is accordingly varied to cause the proper amount of 20 torque to be exerted on the armature.

From the foregoing description, taken in conjunction with the accompanying drawings, it will be manifest that I have provided an electromagnet having a particularly high 25 degree of efficiency.

Although I have herein shown and described only one form of electromagnet embodying my invention, it is understood that various changes and modifications may be 30 made therein within the scope of the appended claims without departing from the spirit and scope of my invention.

Having thus described my invention, what I claim is:

- 35 1. An electromagnet comprising two magnetizable cores each provided with integrally formed end flanges, a back strap bridging said cores at one end, a coil surrounding each core between its flanges, a 40 non-magnetizable strip connecting the other ends of said cores and having a portion thereof disposed between the flanges at such ends, to maintain such flanges in proper spaced relation, and an armature pivotally mounted on said strip.
- 45 2. An electromagnet comprising two magnetizable cores each provided with enlarged magnetizable end flanges, a back strap connecting said cores at one end, a coil surrounding each core between its flanges, a 50 non-magnetizable strip connecting the other ends of said cores and having a portion thereof disposed between the adjacent

flanges, an armature pivotally mounted on said strip and means mounted on said strip 55 for adjusting the closed position of said armature.

3. An electromagnet comprising two cores each provided with a pole-piece and an armature located opposite the faces of said 60 pole-pieces and mounted to swing on an axis substantially opposite one of the edges of said pole-pieces, all edges of the armature except the pivotal edge overhanging the corresponding edges of the pole-pieces. 65

4. An electromagnet comprising two parallel cores, each core having an enlarged flange at each end and both flanges on each core being integral with the body of the core, the two flanges at one end constituting the 70 pole-pieces of the electromagnet, and a back-strap of magnetizable material connecting the other two flanges and contacting therewith throughout substantially the entire area of each flange. 75

5. An electromagnet comprising a pair of magnetizable spools, coils on said spools, a magnetizable member bridging said spools at one end, a non-magnetizable member connecting said spools at the other end, and an 80 armature pivoted to said non-magnetizable member, the pivot point of said armature being located laterally with respect to said spools for the purpose described.

6. An electromagnet comprising two magnetizable cores each provided with an enlarged magnetizable end flange integral with the core, at least one edge of each flange being straight and the straight edges of the two flanges being in mutual contact, and a 90 magnetizable back strap contacting with each flange throughout substantially the entire area of the flange. 85

7. An electromagnet comprising a pair of magnetizable cores each provided with an 95 enlarged magnetizable end flange, and a magnetizable back strap connecting said cores and contacting with each end flange throughout substantially the entire area of the flange. 100

In testimony whereof I affix my signature in presence of two witnesses.

CHARLES W. BURROWS.
